P. W. WERNER

PENCIL

Filed July 30, 1921

UNITED STATES PATENT OFFICE.

PAUL WM. WERNER, OF NIOTA, ILLINOIS.

PENCIL.

Application filed July 30, 1921. Serial No. 488,563.

To all whom it may concern:

Be it known that I, PAUL WM. WERNER, a citizen of the United States, residing at Niota, in the county of Hancock and State 5 of Illinois, have invented a new and useful Pencil, of which the following is a specification.

The device forming the subject matter of this application is a magazine pencil, and 10 one object of the invention is to provide novel means whereby the pencil may be assembled readily and be taken apart with equal facility. Another object of the invention is so to construct the pencil that it will 15 not tire the user when held in the hand. A further object of the invention is to provide novel means for advancing the lead and for holding the lead after the same has been advanced.

20 In the accompanying drawings:—

Figure 1 shows in longitudinal section, a pencil constructed in accordance with the invention, parts appearing in elevation; Figure 2 is a cross section on the line 2—2 25 of Figure 1; Figure 3 is a cross section on the line 3—3 of Figure 1; Figure 4 is a cross section on the line 4—4 of Figure 1; Figure 5 is a cross section on the line 5—5 of Figure 1; and Figure 6 is a fragmental 30 elevation showing the tip.

The device forming the subject matter of this application includes a body, comprising a barrel 1 which may be made of hard rubber if desired. At one end, the barrel 1 is 35 supplied with internal threads 50. The numeral 2 marks a tip having a reduced neck 3 provided with threads 4 engaged with the threads 50 of the barrel 1, the neck being received in the barrel. The neck 3 40 has oppositely disposed longitudinal grooves or seats 5. On the inner end of the neck 3 is mounted a retainer 6 in the form of a disk, this element being made of metal, if desired, and having a polygonal opening 7, 45 which, preferably, is triangular in shape. The disk or retainer 6 has spring fingers 8 received in the grooves 5 of the neck 3 and constituting means for holding the retainer on the inner end of the neck. A tubular 50 liner 9 is disposed within the tip 2 and forms part thereof, the liner terminating in a conical point 10 which may be slit, as indicated at 51, to enhance the hold of the part 10 on the lead when the pencil is in use.

55 A rotatable member is journaled in the barrel 1. The rotatable member 11 is a com-

posite structure and includes a tubular element 12 having a reduced tubular foot 14 provided with internal threads 15. The rotatable member embodies a knob 16 reduced to form a stem 17, the stem terminating in a reduced portion 18 engaged within a thimble 19, an eraser 20 being inserted into the inner end of the thimble 19. The stem 17 of the knob 16 and the thimble 19 fit tightly in the tubular element 12, the construction being such that when rotation is imparted to the knob 16, rotation will be imparted likewise, to the member 11. A reserve supply of leads may be carried in the tubular member 12, the knob 16 and parts carried thereby constituting a closure for retaining the leads in the member 12. It is possible, however, to withdraw the knob 16 and parts carried thereby, to the end that the eraser 20 may be used.

An inner abutment 21 is secured to the foot 14 of the rotatable member. An outer abutment 22 is likewise secured to the foot 14. Between the abutments 21 and 22 is located a bearing 23 wherein the foot 14 of the member 11 is rotatable. In its outer end, the bearing 23 has kerfs 24 so that a properly shaped tool can be inserted into the kerfs 24, thereby to advance the bearing 23 into the barrel 1 until the bearing arrives at the inner end of the threads 50 in the barrel, it being understood that the bearing 23 is threaded into the barrel. The construction above described obviously facilitates greatly the assembling of the pencil.

The pencil includes a plunger embodying a head 26 located within the reduced tubular foot 14 of the rotatable member 11 and engaged with the threads 15 thereof, the plunger including a reduced stem 27 projecting from the head. The stem 27 preferably is triangular in cross section and is slidable in the bore of the liner 9. The stem 27 is received in the triangular opening 7 of the retainer 6 and is held therein against rotation.

When rotation is imparted to the member 11 by means of the knob 16, the plunger 26—27 will be advanced, because the head 26 of the plunger is engaged with the threads 15 and, because the stem 27 of the plunger is held against rotation in the opening 7 of the retainer or disk 6. When the stem 27 of the plunger is advanced, the lead will be crowded forwardly or outwardly in the liner 9, the tip 2 being peculiarly efficient in

holding the lead, because the tip is slit as at 51, at its working end, to form jaws which grip and hold the lead.

I claim:—

5. In a device of the class described, a body; a rotatable member journaled in the body; a bearing threaded into the body, the bearing having a kerf, the rotatable member being journaled in the bearing; an abutment on the rotatable member and coacting with the bearing, the abutment being cut away

to give access to the kerf; a plunger having threaded connection with the rotatable member; and means for holding the plunger against rotation.

In testimony that I claim the foregoing as my own, I have hereto affixed my signature in the presence of two witnesses.

PAUL WM. WERNER.
